M. H. BRANIN,
METHOD OF MANUFACTURING INCANDESCENT LAMPS,
APPLICATION FILED SEPT. 26, 1916.

1,315,813.

Patented Sept. 9, 1919.

INVENTOR:
MARK H. BRANIN,

BY *John G. Davis*

HIS ATTORNEY.

UNITED STATES PATENT OFFICE.

MARK H. BRANIN, OF NEWARK, NEW JERSEY, ASSIGNOR TO GENERAL ELECTRIC COMPANY, A CORPORATION OF NEW YORK.

METHOD OF MANUFACTURING INCANDESCENT LAMPS.

1,315,813.

Specification of Letters Patent.

Patented Sept. 9, 1919.

Application filed September 26, 1918. Serial No. 122,296.

To all whom it may concern:

Be it known that I, MARK H. BRANIN, a citizen of the United States, residing at Newark, county of Essex, State of New Jersey, have invented certain new and useful Improvements in Methods of Manufacturing Incandescent Lamps, of which the following is a specification.

My invention relates to the art of manufacturing electric incandescent lamps and in accordance therewith I have improved the process of manufacture by eliminating certain steps and their attendant disadvantages. My invention also resides in a novel form of bulb used in the manufacturing process.

It has heretofore been the practice to blow the bulbs for electric lamps with necks of considerably greater length than are necessary in the manufacture of the lamp itself, such necks terminating in restricted ends. Such restricted ends have heretofore, as a preliminary step to the manufacture of the lamp been broken off to permit the insertion of the mount in such necks, and the sealing of the mount therein. This is objectionable both from the fact that the breaking off of the end of the neck of the bulb involves an additional step, and because a considerable loss has resulted from the breakage of the bulbs in this step. I propose to construct a bulb ready for the insertion and sealing in of the mount support without necessitating the removal of any part of the bulb prior to this step, and my improved method of manufacture therefore may be said to consist in so blowing the bulb that the mount may be inserted and sealed therein without substantial intermediate change in the bulb, and in sealing the mount thereon; and my invention also consists in a glass bulb, as an article of manufacture, ready for, and adapted to, the insertion of the filament mount therein, whereby lamp bulbs with formed necks may be shipped from the glass blowing factory to the lamp factory ready for the sealing operation and thereby eliminating the necessity of the intermediate step of cracking off the restricted necks.

According to another feature of my invention, I make the neck of such form and weight that the sealing operation is greatly expedited, thereby increasing the capacity of the sealing machines.

Referring to the accompanying drawings in which corresponding parts are designed by corresponding marks of reference:—

Figures 1, 2, 3 and 4 represent successive steps in the manufacture of an electric lamp 60 from the bulbs now commonly employed for that purpose.

Figs. 5, 6, 7 and 8 represent successive steps 65 in the manufacture of an electric lamp from the bulb here described.

It will be proper in order that the scope and nature of my invention may be the better understood, to briefly describe what is now the common practice in the manufacture of electric lamp bulbs. The bulb 70 reaches the factory with a neck considerably greater in length than is required in the completed article, this terminating in a restricted portion *a*, above which is an enlarged zone *b*. After a tube *d* has been 75 sealed in the bottom of the bulb for the purpose of exhausting it, the neck of the bulb is placed within heated metal zones *B*, which, by contacting with the enlarged zone *b* of the bulb, heats the same, this step 80 being represented in Fig. 1. The end of the neck is then broken off by applying a wet wiper *D* to the heated and large zone *b*, this being shown in Fig. 2, and the result is the breaking off of the restricted end of the 85 neck, leaving the bulb in the shape shown in Fig. 3. A mount *E* carrying the filament is now inserted in the neck of the bulb, the bulb itself being held with the neck down, and the bulb is passed between burners *F* 90 which project a flame upon the neck thereof adjacent to the end of the mount, melting the glass at this point, which eventually, by the weight of the neck below, is drawn out with a restriction in diameter, and seals 95 itself to the end of the mount as shown in Fig. 5.

I propose, in lieu of the bulb above shown as an article in which the mount is to be inserted and sealed, a bulb like that shown 100 in Fig. 6, that is to say, a bulb having its lower end terminating in a heavy collar *e*, formed thereon in the process of its manufacture and having a sufficiently great internal diameter to permit the passage of 105 the base of the mount therethrough. Such a bulb after tabulation, is represented in Fig. 6.

In the bulb of this shape may be inserted 110 the filament support without preliminary

steps or operations upon the bulb. A filament so inserted and being sealed is shown in Fig. 7. With the use of the neck ring shown, the period of sealing is somewhat lessened due to the fact that the weight of the neck ring facilitates the drawing out of the neck and aids in the restriction in diameter of the neck at the point where the seal is to be located. This is an improvement over the old way of providing positive means for drawing out the neck. After the sealing, the result of this restriction is the lamp shown in Fig. 8, which it will be seen is identical with the bulb shown in Fig. 15 as the product of the present process.

It will be noted that my invention calls for no additional operation in the manufacture of the lamp, but eliminates several operations which are now necessary. By so doing, it expedites the manufacture of a lamp, and this is also aided by the increased speed of sealing in, due to the weight of the neck 4. Moreover, it is of value in that it permits the shipment to the lamp factory of a bulb which has a formed neck, and in avoiding the necessity of cracking off such neck.

I am aware that glass intended for even-

tual use in the manufacture of electric lamps has been blown with a neck ring thereon, but in so far as I am aware, this neck ring and the neck of the bulb itself were not of a character and shape to permit the insertion of the mount within the neck ring unless the neck ring was first removed. In other words, such neck rings have been present as an incident and an aid to the manufacture of the bulb and not as an incident to the manufacture of the lamp and were necessarily removed from the bulb prior to the insertion of the mount therein.

What I claim as new and desire to secure by Letters Patent of the United States, is:—

The process of manufacturing electric incandescent lamps, which consists in blowing a bulb with an elongated unrestricted neck terminating in a ring therearound having substantial weight, and subsequently without substantial intermediate change of the said bulb inserting a filament mount in the neck, heating the neck, and allowing it to be reduced in diameter by the weight of the ring to seal with the mount.

In witness whereof, I have hereunto set my hand this 21st day of September 1916.

MARK H. BRANIN.
